(57) CLAIM

The ornamental design for a shoe, as shown and described.

DESCRIPTION

FIGS. 1-7 are perspective, lateral side, medial side, front, rear, top, and bottom views, respectively, of a shoe showing my new design.

The white regions bordered by broken lines contain a registered trademark or other indicia and form no part of the claimed design. The “swoosh” logo and the word “NIKE” are registered trademarks of NIKE, Inc.
